UNITED STATES PATENT OFFICE

164,274

BAR OF SOAP OR SIMILAR ARTICLE

Edna Baden, Newton, Mass.

Application November 13, 1950, Serial No. 12,963

Term of patent 7 years

(Cl. D73—1)

To all whom it may concern:

Be it known that I, Edna Baden, a citizen of the United States, residing at Newton, in the county of Middlesex in the Commonwealth of Massachusetts, have invented a new, original, and ornamental Design for a Bar of Soap or Similar Article, of which the following is a specification, reference being had to the accompanying drawing, forming a part hereof, in which:

Figure 1 is a front elevational view, Figure 2 is a rear elevational view and Figure 3 is a side elevational view of a bar of soap or similar article, showing my new design.

I claim:

The ornamental design for a bar of soap or similar article, substantially as shown.
EDNA BADEN.
